United States Patent Office.

JOHN O. FAIRBAIRN, OF MILWAUKEE, WISCONSIN.

Letters Patent No. 97,181, dated November 23, 1869.

IMPROVED DINNER-PAIL.

The Schedule referred to in these Letters Patent and making part of the same.

To all whom it may concern:

Be it known that I, JOHN O. FAIRBAIRN, of Milwaukee, in the county of Milwaukee, and State of Wisconsin, have invented certain new and useful Improvements in Dinner-Pails; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

My invention relates to folding dinner-pails; and consists in constructing them in water-tight compartments, so that they may be mounted, when in use, over each other, or be folded or arranged within each other, in a close and compact manner, for easy carriage and transportation when desired.

In the drawings—

Figure 1 is a longitudinal vertical section of my pail, when its different compartments are mounted upon one another, and

Figure 2 is a vertical section of the same when folded.

In constructing my pail A, I make three or more water-tight compartments, B, C, and D, out of tin or other suitable material, and of an oval or other desired form.

Around each of these compartments, and near their open ends, I sink a groove, *h*, as shown in both figures, so as to form a shoulder for the support of the compartment next above, the upper compartment being provided with a cover, E, having a small receptacle, F, over which fits loosely a cup, G, all as clearly shown in both figures.

To the exterior of the compartment B, I attach, rigidly, two hooks *c*, so as to be opposite to each other, and to the bottoms of the compartments C and D, connect loosely the rings *a*.

The under side of the cover E, I provide with a loose ring, *i*, for raising the cover when turned, and its outside with two loose rings *e*, near its edge, and equidistant from each other, and also with two hooks *k*, for the purposes hereinafter explained.

The compartments and cover thus constructed, I arrange for use, as clearly shown in fig. 1; and for convenience in carrying, as well as for holding them securely together, I attach the ends of a cord or chain, *d*, to the hooks *c*, having first placed upon it a handle,

f, and passed its ends through the rings *e* of the cover, as clearly shown in fig. 1.

As the rings *e* on the cover are, in this arrangement, directly over the hooks *c*, on the compartment B, and as the hooks and rings are on the opposite sides of the pail, as well as opposite to each other, it is obvious that the pail can be conveniently carried by the handle *f*.

When the cords are drawn up tightly, I keep them in that position by means of the hooks *k*, which are so attached to the cover as to be turned and caught into an eye or loop on the cords or chains for that purpose, and in this way also keep the compartments in an upright and fixed position, as clearly shown in fig. 1.

When the pail is not in use, that is, not occupied with anything, it may be taken apart, and folded up, in the following manner:

By releasing the hooks *k*, and then turning the cover E over and fitting it into the compartment D, then turning the compartment D over and fitting it into the compartment C, and then turning the compartment C over and fitting it into the compartment B. When this is done, the whole will be compactly arranged in a small compass, as clearly shown in fig. 2, with the ring *a* on the upper side, and can be conveniently carried or packed for transportation.

The advantages of having a dinner-pail constructed in this way, with different compartments, are obvious. One of them can be used for liquids and the other for articles of different kinds. The liquids and these different articles can be kept entirely separate, and in this way a very desirable purpose be accomplished.

Having thus described my invention,

What I claim, is—

1. A dinner-pail consisting of the compartments B, C, and D, and cover E, all constructed as herein described, so that they may be arranged upon each other, or compactly folded up, as shown and set forth.

2. The compartments B, C, and D, and cover E, provided with the hooks *k*, in combination with the cord or chain *d*, when constructed so as to be arranged as herein shown and described, and for the purpose set forth.

JOHN O. FAIRBAIRN.
